UNITED STATES PATENT OFFICE

2,163,288

RAIL AND WHEEL FLANGE LUBRICATOR

Emmons Overmier, La Grange, and Thomas E. Rodman, Glencoe, Ill., assignors, by mesne assignments, to Poor & Company, Chicago, Ill., a corporation of Delaware

Application June 4, 1937, Serial No. 146,422

15 Claims. (Cl. 184—3)

This invention relates to rail and wheel flange lubricators and particularly to apparatus of this character adapted to discharge lubricant laterally onto the gauge side of a rail head from a location intermediate the side faces of said rail head.

In certain apparatus of the above general character heretofore proposed, the side face of the rail head is formed with a long recess and a distributing bar fitted into such recess in a manner to provide a series of elongated openings through which the lubricant is discharged outwardly with relation to the rail head. Such apparatus is difficult to construct and install since the recess in the side of the rail head extends the full length of the distributing bar, usually 6 to 12 feet long and must be formed with a high degree of accuracy. It is impractical to form a recess of such length in a rail head while the rail is positioned in the track. The usual and customary practice is to remove a section of the rail and insert in its place a rail section which has been previously recessed and the lubricant distributing bar fitted therein at the factory. This practice is very undesirable in that it involves considerable labor and expense in removing the rail section, transporting it to the factory to be recessed and in handling and transporting the rail sections with the distributing bar attached.

One of the objects of the present invention is to provide, in an apparatus of the above general character, improved constructions whereby suitable recesses can be formed in the rail head and the lubricant distributing member fitted therein without disturbing the position of the rail in the track. In this connection, the present invention includes the provision of a lubricant distributing bar positioned in the fishing space at one side of a rail with capacity for vertical and angular adjustment and provided with a plurality of upwardly extending pocket elements from which the lubricant is discharged. The said pocket or delivery elements are relatively thin transversely of the rail head and are adapted to fit into shallow recesses formed at spaced locations in the side face of the rail head. The said recesses being of shallow depth and of relatively short length, in relation to the length of the distributing member, can be readily and conveniently formed with portable grinding and cutting devices.

Another object of the invention is to provide a lubricant distributing member having a novel and compact arrangement of lubricant supply and branch ducts which are so proportioned as to provide uniform resistance to the movement of lu-

bricant and thereby deliver uniform quantities of lubricant to the several discharge pockets.

Another object is to provide a lubricant distributor of the above character which can be interchangeably fitted on rails of different sizes and which may be adjusted vertically of the rail so as to insure discharge of the lubricant at such locations relative to the top of the rail head as will be most suitable for the particular speed of traffic and other conditions at the location where the lubricating apparatus is installed.

Other objects and advantages of the invention will be apparent from the detailed description of the embodiments of the invention shown in the drawings, wherein:

Fig. 1 is a plan view of a portion of a railroad track showing a track and wheel flange lubricating apparatus, constructed in accordance with this invention, applied on the rail.

Fig. 2 is a fragmentary side view of mechanism adapted to be operated, by the passing of a train over the track, to operate a lubricant pump.

Fig. 3 is a side view of a lubricant distributing bar constructed in accordance with this invention showing certain discharge pockets of the distributor arranged in the several recesses formed in the rail head.

Fig. 4 is a longitudinal section taken on line 4—4 of Fig. 3 to illustrate the main and branch ducts for the lubricant.

Fig. 5 is a cross-sectional view taken on line 5—5 of Fig. 1 looking in the direction of the arrow and illustrating the manner in which the lubricant distributor and the wheel actuated mechanism, for operating the lubricant pump, are secured to the base portion of a rail.

Fig. 6 is a view similar to Fig. 5 but illustrating a lubricant distributor modified in construction so that the lubricant discharge openings of the lubricant pockets may be raised and lowered with relation to the top surface of the rail head, and

Fig. 7 is a detail view of one element used in forming the lubricant pockets.

The embodiment of the invention shown in Figs. 1 to 5 inclusive may be described briefly as comprising a lubricant supply reservoir 9, a pump 10, of suitable construction, associated with the supply reservoir, a pump operating mechanism 11 extending from the pump to a position adjacent a railroad rail and adapted to be actuated by trains passing over the rail, one or more lubricant distributing members 12 arranged along the gauge side of the railroad rail so as to direct lubricant into the space between the side face of the

30

35

55

rail head 13 and the flanges of car wheels passing over the rail; and suitable piping, for example, pipes 14-14 for connecting the lubricant pump 10 with the distributing member, or members 12, as the case may be.

The reservoir 9 is preferably arranged at one side of the track and is embedded in the ground at a suitable distance from the track so as to be free of all movements of the track structure. The 10 pump 10 may be of any suitable construction and is mounted in close relation to the lubricant supply, preferably, on the side of the reservoir 9. A flexible shaft structure 15, forming a part of the operating mechanism 11, extends from the 15 pump 10 to a supporting bearing 16 fixed to the rail 13. The flexible shaft structure, in addition to the flexible joint members 17-17 includes a shaft section 18 which slidably receives the shaft section 19 so that the shaft structure 20 will automatically adjust its length to compensate for any vertical or lengthwise movements of the rail 13. The section 19 of the shaft structure is provided at its inner end with a lever arm 20 which is engaged by a lever 21 pivoted at 22 in a bracket 23 fixed to the rail and the said lever 21 is normally supported in a position whereby the portion 24 thereof will extend above the top surface of the rail head and in the path of travel of the car wheels. In the present embodiment the lever 21 and the lever arm 20 are maintained in the position indicated in Fig. 2 by means of a spring (not shown) associated with the pump 10.

It will be observed, from the above description, 35 that car wheels passing along the rail 13 will depress the lever 21 and thereby rock the lever 20 and the flexible shaft structure 11 in a manner to impart an operating movement to the pump 10. The operation of the pump withdraws lubricant from the reservoir 9 and forces it through 40 the supply pipes 14-14 to the inlet ports of the distributing members 12 of the apparatus.

The lubricant distributing members 12-12 are 45 preferably identical in construction. It will be sufficient, therefore, to describe the details of construction of only one of these members.

The lubricant distributor comprises a bar structure 25 which extends lengthwise of the rail, and a plurality of lubricant pockets designated A, 50 B, C and D which extend upwardly from the bar into recesses 26 formed at spaced locations in the sideface of the rail head 13. The said recesses open through the side and bottom surfaces of the rail head but terminate at a suitable 55 distance below the top surface thereof. The depth of the recesses, transversely of the rail, correspond substantially to the thickness of the lubricant pocket members so that the outer faces of the pockets will extend in the plane of the side 60 face of the rail head. It is not essential, however, that the recesses 26 conform to accurate measurements throughout, since the area of the lubricant discharge passages of the several pockets depends upon the construction of the pocket 65 members and their positions in the recesses. For this reason, the recesses may be formed in the rail head by using portable grinding and cutting implements and without disturbing the position of the rail in the track.

70 Each of the lubricant pockets A, B, C, and D comprises a front plate 27, a back plate 28, and a spacing plate 29, the latter of which is cut away, as indicated by the reference numeral 30, in Fig. 7, to provide the lubricant space of a pocket. The 75 said plates 27, 28 and 29 are preferably secured

together with spot welds 31 and the several pocket assemblies are clamped in their properly spaced relation between plates 32 and 33 of the bar structure 25.

Lubricant is carried from the supply pipe 14 to the several pockets through main and branch ducts formed in the bar structure 25 of the distributor. The main or supply duct designated 34 in the drawings is a channel formed in the inner face of the front plate 35 of the bar structure. This duct extends lengthwise of the bar near its upper edge to points midway between the pockets A-B and C-D. The open side of the duct is closed by means of a closure plate 36. This plate also serves as a closure for branch ducts 37-37 formed in the outer face of plate 33. The said branch ducts connect the pockets A-B and C-D and communicate, through openings 38 in the closure plate 36, with the extremities of the main duct 34. By making the main and branch ducts in the form of open channels, they can be readily and accurately formed of proper lengths and cross-sectional areas to equalize the flow of lubricant to each of the several pockets. The main and branch lubricant ducts are preferably arranged in the same horizontal plane. This arrangement makes it practicable to position both ducts near the upper edge of the bar structure 25, whereby the vertical dimensions of the bar may be minimized and thereby permit the bar as a 30 whole to be adjusted vertically in the fishing space of the rail. The said arrangement of lubricant ducts in the bar structure presents a further advantage in that the several plates of the bar structure may be clamped together by means 35 of bolts 39 extending through the several plates 32, 33, 35 and 36 of the bar at locations below lubricant supply and branch ducts.

The lubricant distributor and the wheel actuated mechanism are secured to the rail, with 40 capacity for adjustment thereon by means of supporting clamps 40 and 41. The supporting clamp 41 comprises a jaw member 42 adapted to engage one flange of a rail base and has an upwardly extending arm 43 which is slotted at 44 to receive 45 a bolt 45 for clamping the bracket member 23 to the said arm of the clamp jaw. At the other side of the rail a jaw member 46 engages over the rail base in a position to support the lubricant distributor of the apparatus. The jaw members 42-46 of the clamp are held in clamping engagement with the rail base by means of a wedge bolt 47. The supporting clamp 40 may be and preferably is the same in construction as the clamp just described except that the jaw member designated 42a has no upwardly extending portion 43.

The lubricant distributor is adjustably secured to the jaw members 46 of the brackets 40-41 by means of angle members 49-49, secured to the front plate of the bar structure 25, and clamping 60 bolts 50-50. Suitable shims 51-52 are interposed between the angle members and the top surface of the clamp jaws for adjusting the vertical and angular positions of the distributing bar with relation to the upper extremity of the recesses 26 and with relation to the side face of the rail head. In Fig. 5 the shim 52 is bent upon itself at one end to form a wedge adapted to support the distributor at a suitable angle, whereby the outer faces of the pockets are held at an 70 angle corresponding to the inclination of the side face of the rail head.

The operation of the apparatus may be summarized as follows: The wheels of a train passing along a track engage and depress the lever 21. 75

This movement of the lever imparts a partial rotation to the flexible shaft 11 which in turn operates the pump 10 to force lubricant through the supply pipe 14, main lubricant duct 34 and branch duct 37-37, into the pockets A, B, C and D. The lubricant discharged from the said pockets is directed laterally and upwardly into the space between the rail head and the wheel flanges by the top walls 55 of the recesses 26. When a heavy lubricant is used, for example, a heavy grease, the grease extruded from the pockets forms a ridge or bead which extends across the pockets and along the gauge side of the rail head. This body of grease will retain its form on the side of the face of the rail head and will have wiping contact with the wheel flanges. Lubricant, in small amounts, is picked up by passing wheel flanges and re-applied to the side of the rail head at locations remote from the lubricating apparatus.

The modified embodiment shown in Fig. 6 of the drawings is the same in all respects as the embodiment shown and described in connection with Figs. 1 to 5 inclusive, except that the back walls 57 of the lubricant pockets are formed at their upper ends with angular portions 58 which overlie the discharge openings of the pockets so as to direct the lubricant laterally and upwardly into the space between the side face of the rail head and the wheel flanges. In accordance with this embodiment the discharge opening 59 of the pockets may be readily and conveniently adjusted vertically with relation to the top surface of the rail head. This manner of adjustment permits the lubricant distributor to be accurately set, with regard to the speed of the traffic and other conditions at the location of the lubricator and thereby insures efficient lubrication of the track by applying such quantities of lubricant to the wheel flanges as will be best suited for the particular service conditions.

We claim:

1. A rail and wheel flange lubricating apparatus comprising a railroad rail, the head portion of which is recessed at locations spaced longitudinally of the rail, which recesses open through the gauge side face and the under surface of the rail head adjacent said face and terminated at locations below the top surface of the head, and a lubricant distributing member extending lengthwise of the rail and provided with lubricant delivery members having lubricant ducts therein leading to the upper ends thereof and the said members extending upwardly into said recesses to points adjacent the upper ends thereof, whereby lubricant discharged from said delivery members is directed laterally and upwardly to the side face of the rail head.

2. A rail and wheel flange lubricating apparatus comprising a railroad rail, the head portion of which is recessed at locations spaced longitudinally of the rail, which recesses open through the gauge side face and the under surface of the rail head adjacent said face but terminate at locations below the top surface of the head, and a lubricant distributing member extending lengthwise of the rail and provided with lubricant delivery members having lubricant ducts therein leading to the upper ends thereof and the said members extending upwardly into said recesses to points adjacent the upper ends thereof, and with the outer faces of said delivery members extending in the plane of the side face of the rail head.

3. A rail and wheel flange lubricating apparatus comprising a railroad rail, the head portion

of which is recessed at locations spaced longitudinally of the rail, which recesses open through the gauge side face and the under surface of the rail head adjacent said face but terminate at locations below the top surface of the head, and a lubricant distributing member extending lengthwise of the rail and provided with lubricant delivery members having lubricant outlet ports in their upper ends and the said members extending upwardly into said recesses to points adjacent the upper ends thereof, and means for adjustably supporting said distributing member on the rail, whereby the positions of the outlets of said lubricant ducts relative to the upper ends of the recesses may be varied.

4. A rail and wheel flange lubricating apparatus comprising a railroad rail, the head portion of which is recessed at locations spaced longitudinally of the rail, which recesses open through the gauge side face and the under surface of the rail head adjacent said face but terminate at locations below the top surface of the head, and a lubricant distributing member extending lengthwise of the rail and provided with lubricant delivery members having lubricant ducts therein leading to the upper ends thereof and the said members extending upwardly into said recesses to points adjacent the upper ends thereof, the said delivery members being in the form of relatively wide but thin pockets with their outer faces extending in the plane of the side face of the rail head, supporting brackets on which the distributing member is mounted, and means interposed between the brackets and the distributing member for adjusting the vertical and angular positions of the said pockets relative to the rail head.

5. A rail and wheel flange lubricating apparatus comprising a railroad rail, the head portion of which is recessed at locations spaced longitudinally of the rail, which recesses open through the gauge side face and the under surface of the rail head adjacent said face but terminate at locations below the top surface of the head, and a lubricant distributing member extending lengthwise of the rail and provided with pockets having outlet openings for discharging lubricant laterally therefrom, and means for adjustably supporting said pockets in said recesses whereby the positions of the outlet openings may be varied with relation to the top of the rail head.

6. In a rail and flange wheel lubricating apparatus, a lubricant distributor comprising a bar structure for extending lengthwise of a rail and having a plurality of lubricant outlet pockets adapted to extend into recesses formed in the lower portion of the gauge side face of a rail head, there being a lubricant supply duct formed in and extending lengthwise of the bar and branch ducts of uniform length leading from the extremities of the supply duct to the said outlet pockets.

7. In a rail and wheel lubricating apparatus, a lubricant distributor comprising a bar structure for extending lengthwise of a rail and having a plurality of lubricant outlet pockets adapted to extend into recesses formed in the lower portion of the gauge side face of a rail head, there being a lubricant supply duct formed in and extending lengthwise of the bar and branch ducts extending lengthwise of the bar at locations intermediate the supply duct and said pockets for connecting the pockets with the supply duct.

8. In a rail and wheel flange lubricating apparatus, a lubricant distributor comprising a bar structure for extending lengthwise of a rail and having a plurality of lubricant pockets adapted to extend into recesses formed in the lower portion of the gauge side face of the rail head, there being a lubricant supply duct formed in and extending lengthwise of the bar and branch ducts extending in the horizontal plane of the supply duct and connecting the supply duct with the lubricant pockets.
9. In a rail and wheel flange lubricating apparatus, a lubricant distributor comprising a bar structure extending lengthwise of the rail, a plurality of lubricant pockets extending upwardly from the bar structure and adapted to extend into relatively shallow recesses formed in the side face of the rail head, each of said pockets comprising a front plate, a back plate, and an intermediate spacer plate having a recess extending downwardly from its upper edge and defining the size of the lubricant pocket, there being a main lubricant duct extending lengthwise of the bar and branch ducts leading from the extremities of the main duct to the lubricant pockets.
10. In a rail and wheel flange lubricating apparatus, a lubricant distributor comprising a bar structure extending lengthwise of the rail, a plurality of lubricant pockets extending upwardly from the bar structure and adapted to extend into relatively shallow recesses formed in the side face of the rail head, each of said pockets comprising a front plate, a back plate, and an intermediate spacer plate having a recess extending downwardly from its upper edge and defining the size of the lubricant pocket; the upper edge portion of the back plate being turned outwardly toward the side face of the rail to direct the lubricant laterally and upwardly when it is discharged from the said pockets.
11. In a rail and wheel flange lubricating apparatus, a lubricant distributor comprising in combination a bar structure extending lengthwise of the rail, a plurality of lubricant pockets extending upwardly from the bar structure and adapted to extend into relatively shallow recesses formed in the side face of the rail head, each of said pockets comprising a front plate, a back plate, and an intermediate spacer plate, a portion of which is cut away to define the size of the pocket, and means for raising and lowering the pockets relative to the top of the rail head so as to vary the elevation of the discharge opening of said pockets.
12. In a rail and wheel flange lubricating apparatus, a lubricant distributing member comprising a plurality of pocket elements from which lubricant is adapted to be discharged into the space between a side face of the rail head and the flanges of the wheels passing along the rail, and a bar structure for supporting said pocket elements comprising a front plate having a channel in its inner face to provide a main supply duct for lubricant, a closure plate for said channel, a second plate having lubricant branch ducts therein for connecting said lubricant pockets in pairs, and means for clamping the said plates to-

gether, there being openings in the closure plate through which the said branch ducts communicate with the lubricant supply duct.

13. In a rail and wheel flange lubricating apparatus, a lubricant distributing member comprising a plurality of pocket elements from which lubricant is adapted to be discharged into the space between a side face of the rail head and the flanges of the wheels passing along the rail, and a bar structure for supporting said pocket elements comprising a front plate having a channel in its inner face to provide a main supply duct for lubricant, a closure plate for said channel, a second plate having spaced channels which are closed by said closure plate to provide lubricant branch ducts for connecting said lubricant pockets in pairs, and means for clamping said plates together, there being openings in the closure plate through which the said branch ducts communicate with the lubricant supply ducts and openings leading from the extremities of the branch ducts to the said pockets.

14. In a rail and wheel flange lubricating apparatus, a lubricant distributing member comprising a plurality of pocket elements arranged in spaced relation to each other at one side of the rail and adapted to direct lubricant into the space between a side face of a rail head and the flanges of car wheels passing along the rail, a pair of plates between which the pocket elements are clamped, the outer plate of which is formed with spaced channels in its outer face, each channel connecting a pair of lubricant pockets, a closure plate for closing said channels, a front plate formed in its inner face with a lubricant supply channel which is closed by said closure plate, there being openings through the closure plate for connecting the extremities of the supply channel with the said spaced channels at locations midway between the connected lubricant pockets, and means for clamping the said pockets and plates in their assembled relation.

15. In a rail and wheel flange lubricating apparatus, a lubricant distributing member comprising a plurality of pocket elements arranged in spaced relation to each other at one side of the rail and adapted to direct lubricant into the space between a side face of a rail head and the flanges of car wheels passing along the rail, a pair of plates between which the pocket elements are clamped, the outer plate of which is formed with spaced channels in its outer face, each channel connecting a pair of lubricant pockets, a closure plate for closing said channels, a front plate formed in its inner face with a lubricant supply channel which is closed by said closure plate, there being openings through the closure plate for connecting the extremities of the supply channel with the said spaced channels at locations midway between the connected lubricant pockets, and means for clamping the said pockets and plates in their assembled relation comprising bolts extending through the said plates and pockets at locations below the said supply and spaced channels.

EMMONS OVERMIER.
THOMAS E. RODMAN.

CERTIFICATE OF CORRECTION.

Patent No. 2,163,288.

June 20, 1939.

EMMONS OVERMIER, ET AL.

It is hereby certified that error appears in the printed specification of the above numbered patent requiring correction as follows: Page 3, first column, line 48, claim 1, for the word "terminated" read terminate; same page, second column, line 53, claim 6, for "flange wheel" read wheel flange; line 64, claim 7, after "wheel" insert flange; and that the said Letters Patent should be read with this correction therein that the same may conform to the record of the case in the Patent Office.

Signed and sealed this 15th day of August, A. D. 1939.
